ATTORNEY

UNITED STATES PATENT OFFICE.

WASHINGTON FOGLESONG, OF DAYTON, OHIO.

LEATHER-NET CLAMP.

SPECIFICATION forming part of Letters Patent No. 250,515, dated December 6, 1881.

Application filed June 27, 1881. (No model.)

To all whom it may concern:

Be it known that I, WASHINGTON FOGLESONG, a citizen of the United States, residing at Dayton, in the county of Montgomery and State of Ohio, have invented a new and useful machine entitled a "Leather-Net Clamp," for holding the longitudinal strips of leather used in fly-nets while the strings are being put into the same, of which the following is a specification.

My invention relates to a compound clamp in which the longitudinal strips of leather are held, after being suitably punctured, for the purpose of drawing the strings into the same, the object being to expedite the operation and produce a more perfect net. I attain the object by the mechanism illustrated in the accompanying drawings, in which—

Figure I is a top view of the leather-net clamp. Fig. II is a transverse section of the same on the line *x x*. Fig. III is an enlarged view of a pair of the clamping-bars.

At Fig. I are represented a series of clamping-bars, I, which are of sufficient length to receive between the same the longitudinal straps of a fly-net, and in cross-section are like the letter I. To the bottom of each of these are bolted a series of flanged guides, F, which may be four in number, or less. Within these guides are placed the binding-rod T, one only of which is shown in the drawings. The rear bar has a series of projections, at which point the binding-rods are situated. Onto the ends of these rods are placed a clamping-handle, J, held by a nut. This handle has an inclined projection extending over half of its inner surface, which bears against the projection of the clamping-bar, and thereby presses them together when rotated in one direction, and when the motion is reversed the bars can be separated.

The clamping-rod may be securely attached to the rear bar, or its bent end may engage the rear surface of the bar.

The faces of the clamping-bars may be parallel, as represented at Fig. II, or the upper

edge of one may be cut away to the depth it is desirable to have the leather enter the clamp, and the other have a projection suitable thereunto, as illustrated at Fig. III. In this figure 50 is shown a piece of leather as it is held in the clamp.

In using the clamp with parallel faces it is necessary to put pins in the holes punctured for the strings as a means of preventing the 55 leather falling too deep into the clamp. The clamping-bars are adapted in width to the form of a horse, widening from the head to the tail, and the clamping-bars may be narrowed slightly near the back end, corresponding to 60 the slope of the rump.

The operation is thus: The prepared strips are placed in the clamp and the handle is turned, and they are thus securely held, and while in this position the strings are drawn 65 through the holes, and this accomplished the net is taken from the clamp in a finished condition.

The nut alone or other device than that of the clamping-handle may be used to tighten 70 the clamping-bars.

Having fully described my invention, what I claim, and desire to secure by Letters Patent, is—

1. The leather-net clamp consisting of a series of clamping-bars, I, with guides F and rods T, in combination with suitable devices for tightening the same, substantially as set forth. 75

2. The leather-net clamp consisting of a series of clamping-bars, I, with guides F and rods T, in combination with the clamping-handle J, substantially as set forth. 80

3. The clamping-bars I, with notches and suitable projections on their faces, substantially as shown and described, and for the purpose set forth. 85

WASHINGTON FOGLESONG.
